DESIGN FOR A HAT DISPLAY STAND

Terance H. Robsjohn-Gibbings, New York, N. Y.,
assignor to John Frederics Inc., New York,
N. Y., a corporation of New York

Application January 18, 1940, Serial No. 89,553

Term of patent 7 years

To all whom it may concern:

Be it known that I, Terance H. Robsjohn-Gibbings, a subject of Great Britain and resident of the city, county, and State of New York, have invented a new, original, and ornamental Design for a Hat Display Stand, of which the following is a specification, reference being had to the accompanying drawing, forming part thereof.

The figure is a perspective view of a hat display stand showing my new design.

I claim:

The ornamental design for a hat display stand, substantially as shown.

TERANCE H. ROBSJOHN-GIBBINGS.
